UNITED STATES PATENT OFFICE.

OSCAR M. FURR, OF HOUSTON, TEXAS.

ACETYLENE-GAS GENERATOR.

1,292,302.

Specification of Letters Patent. Patented Jan. 21, 1919.

Application filed November 13, 1916. Serial No. 130,944.

To all whom it may concern:

Be it known that I, OSCAR M. FURR, a citizen of the United States, residing at Houston, in the county of Harris and State 5 of Texas, have invented certain new and useful Improvements in Acetylene-Gas Generators, of which the following is a specification.

This invention relates to new and useful 10 improvements in an acetylene gas generator.

The object of the invention is to provide a generator of the character described whereby carbid may be fed automatically into the water tank so as to keep the gas pressure 15 within the tank substantially uniform.

Another object of the invention resides in the provision of means whereby the feed valve will be automatically cleaned so as to prevent the carbid from adhering thereto 20 and clogging the discharge outlet.

With the above and other objects in view the invention has particular relation to certain novel features of construction, operation and arrangement of parts an example 25 of which is given in this specification and illustrated in the accompanying drawings wherein:—

Figure 1 is a side elevation of the device.

Fig. 2 is a vertical sectional view thereof. 30 Fig. 3 is a transverse sectional view taken on the line 3—3 of Fig. 2, and

Fig. 4 is an enlarged fragmentary sectional view showing the discharge opening of the carbid hopper and the valve mechanism controlling the same. 35

Referring now more particularly to the drawings wherein like numerals of reference designate similar parts in each of the figures, the numeral 1 refers to a cylindrical tank, 40 which is open at the top and the upper portion of which has fixed within the same, a supplemental wall 2 concentric with and spaced from the wall of the tank 1, forming an annular chamber 3 which surrounds the 45 supplemental wall 2. The numeral 4 refers to the tank covering having an annular depending rim 5 which fits closely within the tank 1 and whose lower free edge rests upon the annular partition 6, separating the chamber 3 from the tank 1, when the covering is 50 completely seated on the tank. The hopper 7 is fixed to the covering and forms therewith, an inclosed chamber which may be filled with the carbid through the opening 8 in the covering, said opening being normally closed by the plug 9. This hopper has a discharge opening 10 which is controlled by the valve 11. This valve is cylindrical in form and fits closely in the sleeve 12 which is fixed to and depends from the support 13 60 which spans and is fixed relative to the hopper 7. The lower end of the valve 11 is tapered to conform to the tapering walls of the hopper 7 so as to form a perfect fit thereagainst when the valve is seated and 65 completely close the discharge opening 10. Depending from one side of the hopper is the arm 14 to the lower end of which one end of the lever 15 is pivoted. A valve stem 16 is fixed to the lower end of the valve and 70 extends through the outlet opening 10 and the lower end thereof is pivoted to the lever 15. The free end of this lever has a weight 17 which normally holds the valve closed. The upper edge of the supplemental wall 2 75 carries a drier formed of an annular chamber 18 filled with compressed cotton or some similar material as 19 and the bottom wall of this chamber has a plurality of perforations 20 through which the generated gas 80 passes into the drier. An outlet pipe 21 projects up into said drier and its lower end passes through the tank 1 near the bottom and terminates in the outlet 22 which is controlled by the valve 23. The tank 1 is partially 85 filled with water through the inlet spout 24 and the chamber 3 is also filled with water. When there is no gas pressure in the tank, the covering 4 will be completely seated as shown in Fig. 2, and the weight 17 will 90 be held elevated relative to the discharge opening 10 by means of the upper edge of the supplemental wall 2. The hopper 7 should then be filled with carbid and a portion thereof will escape through the opening 95 10 and fall into the water in the tank 1 and gas will be immediately generated and the pressure thereof will lift the covering 4 and when the covering is sufficiently elevated to raise the weight 17 clear of the upper edge of 100 the supplemental wall 2, said weight will operate to close the opening 10 through the valve 11 and the carbid supply will be automatically cut off. The gas thus generated will pass up through the perforations 20 and 105 through the drier and then through the outlet pipe 21 to the place where it is to be utilized. As the gas pressure decreases, the covering 4 will lower of its own weight until the weight 17 comes into contact with the 110 supplemental wall again and the valve 11 will be lifted, admitting an additional sup-

ply of carbid through the opening 10 thus increasing the gas pressure to normal and again elevating the covering 4. As the valve 11 is elevated it is forced up into the sleeve 12, the lower edge of which cleans the valve and relieves it of any carbid which may have adhered thereto on account of corrosion, thus at all times keeping the valve clean and preventing any clogging of the carbid around 10 the discharge opening 10.

Leading from the bottom of the tank 1 is an outlet pipe 25 through which the sludge may be drawn off from said tank. In the bottom of the tank is the usual sludge stirrer 15 26, which is fixed to and manipulated by the handle 27 and by means of which the sludge is agitated preparatory to drawing it off. The chamber 3 being filled with water in which the depending rim 5 is always submerged forms in effect a seal which prevents 20 the escape of any of the gas.

What I claim is:

A device of the character described including a tank, a vertically movable covering fitted within the tank, a carbid hopper carried by the covering and having a discharge 25

opening in the lower part thereof, a depending sleeve fixed relative to the hopper and alined over and spaced from said opening, a valve whose lower end is tapered to conform to the shape of said opening and whose upper end is fitted closely, into said sleeve, said valve controlling said opening, a lever pivotally secured at one end to said hopper and whose other end is free, a weight carried 30 by said free end, a valve stem, one end of which is attached to the valve, and the other end of which projects through said opening and is pivoted to said lever, at an intermediate point, and means carried by the tank 40 against which the free end of the lever engages when the covering descends to lift said valve from the opening and forces it into said sleeve, said sleeve acting as a scraper to cleanse the valve of matter adhering thereto. 45

In testimony whereof I have signed my name to this specification in the presence of two subscribing witnesses.

OSCAR M. FURR.
